UNITED STATES PATENT OFFICE.

OTTO KOHSE, OF CHEHALIS, WASHINGTON.

STUMP BURNER.

Application filed April 9, 1923. Serial No. 631,041.

To all whom it may concern:

Be it known that I, Otto Kohse, a citizen of the United States, residing at Chehalis, in the county of Lewis and State of Washington, have invented certain new and useful Improvements in Stump Burners, of which the following is a specification.

In carrying out the present invention, it is my purpose to provide a highly improved burner, that is primarily although not specifically adapted for the burning of tree stumps, the invention being so characterized as to embrace the desired features of simplicity, durability and efficiency, the same comprising relatively few parts, and these being correlated in such a manner as to reduce the liability of derangement to a minimum.

A further purpose of my invention is the provision of a stump burner that may be readily transported from place to place in a simple and expeditious manner, and thereby permit the burning of stumps upon great land acreage.

The nature and advantages of the invention will be better understood when the following detailed description is read in connection with the accompanying drawings, the invention residing in the construction, combination, and arrangement of parts as claimed.

In the drawings forming part of this application, like numerals of reference indicate similar parts in the several views,

Figure 1 is a side elevation of my device, minus the burner and air nozzles.

Figure 2 is a top plan view of the oil tank, together with its directly associated parts.

Figure 3 is an elevation, partly in cross section of a form of burner nozzle, employed in conjunction with this invention, and

Figure 4 is a similar view of an air nozzle, also forming a part of my invention.

Referring to the drawings in detail, 5 indicates a truck frame 6, the front supporting and steering wheels therefor, and 7 the rear supporting wheels. However, I do not wish to limit myself to any particular form of supporting truck, as in the future practice of the invention, the same will be modified from time to time without affecting the spirit and scope of the appended claims.

Upon the rear end of the truck frame 5, is a tank 8 of relatively large capacity, the same being secured to the frame, through the medium of rods 9 that will extend

through the body of the said tank 8. The upper end of this tank is provided with a filler opening that is normally closed by a cap 10, the upper end of the tank being also 60 equipped with an air inlet nipple 11.

Slightly forward of the tank 8 and secured upon the truck frame in any manner desirable, is an air compressor designated generally by the numeral 12, this air compressor including the usual pulley wheel 13, over which is trained a belt 14. This belt extends forwardly of the truck frame, and is in turn trained over a pulley 15, upon one end of the power shaft of a combustion engine 16.

Communicating at one end with the usual outlet of the compressor 12 is an air feeder pipe 17, the same extending upwardly and thence rearwardly and being connected at its 75 opposite end to a coupling 18 upon the said outlet nipple of the tank 8, this pipe being provided with a check valve 19.

Secured to the coupling 18 are oppositely extending pipes 20 and 21, the pipe 20 being equipped with a pressure gauge 22, while the pipe 21 is equipped with a safety blow off valve. Also secured to the coupling 18, and extending forwardly thereof is a pipe section 24, upon the front end of which 85 is a similar coupling 25, and secured thereto, and extending in opposite directions therefrom are pipe sections 26, which are provided with pet cocks 27, the front end of said coupling 25 being also equipped with a 90 similar pet cock, there being secured to each of these pet cocks a flexible hose 28.

Upon the front side of the tank 8, and adjacent the lower end thereof is an outlet pipe 29, upon the projecting end of which is a coupling 30 that carries oppositely extending pipe sections 31, upon the end of which are globe valves 32, to which are secured hose lengths 33, it being of course understood that the coupling 30 may be changed 100 for permitting of a greater or lesser number of valves 32 to be secured thereto.

Upon the free ends of the air hose elements 28 are nozzles 34, the same being of a relatively elongated nature, and of any desirable construction compatible with the purposes of my invention.

In Figure 3, there is shown a specific form of oil burner, that comprises an elongated pipe section 34, one end thereof being internally screw threaded for the reception of the burner tip 35, this plug being provided with

the oil passage having its inner end shaped to provide a valve seat 36. Adjacent the end of the said pipe 34 carrying the burner tip 35 is a sleeve or collar 38 of a head retaining metal, and being welded or otherwise secured to said pipe section. Upon the upper end of the pipe section 34 is the usual head 39, to which is attached the free end of one of the hose sections 33, it of course being understood that each hose 33 carries a burner of the type shown in Figure 3. Movable within the pipe section 34 is a valve rod 40, one end of the same being formed so as to engage the said valve seat 36 of the burner tip 35, for cutting off the flow of oil in the manner to be presently described.

Adjacent the upper end of the said valve rod 40, the same is formed with an enlarged screw threaded portion 41, that has engagement within a screw threaded opening of the said head 39, the upper end of this rod projecting outwardly of the head and being provided with an operating wheel 42. In employing my device in the burning of tree stumps, it is first necessary that a hole be dug in the ground in a direction towards the heart of a stump, and preferably between the two main extending roots. Before opening the respective valve from the oil tank 8 to the burner being used, the sleeve or collar 38 is heated to practically a red heat, after which, the valve is opened, and the valve rod 40 of the burner adjusted to the desired position. The burner is then inserted within the hole, together with one of the air nozzles 33, it being of course understood that the compressor 12 is being operated, and that the respective pet cock 27 is open. The air nozzle 33 is also extended into the opening within said burner, and the oil passing through the tube 34 will be vaporized, whereby the same will be mixed with the air from the nozzle for producing a highly ignitable fluid. After the stump has been burning for a certain length of time, the oil burner may be removed from the hole, the air from the nozzle 33 assisting in the burning of the stump.

Although I have shown and described my

device as being primarily adapted for the burning of tree stumps, it is nevertheless to be understood that the tank 8 may carry a supply of disinfectant material, which will be discharged through the oil and air nozzles for spraying trees, plants or the like, it being also obvious that the device may be used for kindred purposes.

I do not wish to limit myself to the specific construction of the device as set forth, as minor changes may be made therein, without departing from the spirit and scope of the invention as claimed.

Having thus described my invention, what I claim as new, and desire to secure by Letters-Patent, is:—

A portable stump burner including a wheeled frame, an oil tank mounted on the rear end portion of said frame, securing means extending through said tank and the frame for securing said tank thereto, and an air compressor mounted on said frame, means for driving said air compressor, a fitting mounted on the upper end of said tank and having communication therewith, a pipe connecting said fitting to said air compressor for conveying the air compressed to the tank, said fitting having a plurality of valved outlets, air hose secured to each of said outlets, a pressure relief valve mounted in said fitting, an outlet mounted at the bottom of the tank, hose connections with said outlet having a valve for controlling the outlet of fluid from the tank, and burner nozzles mounted on the end of said last mentioned hose whereby the air compressed in said compressor will be conveyed to the tank and air hose and maintained under a predetermined pressure for forcing oil through the last mentioned hose when the valve controlling communication thereto is opened and forcing air thru the first mentioned hose when the valve controlling the outlet thereto is open, the burner nozzles providing a fuel oil flame for burning the stump and the first mentioned hose connection providing the air for said flame.

In testimony whereof I affix my signature.

OTTO KOHSE.
